BASE FOR A PHONOGRAPH TURNTABLE OR SIMILAR ARTICLE

Monte Levin, New York, N.Y., assignor to British Industries Corporation, Westbury, N.Y., a corporation of New York

Filed July 3, 1967, Ser. No. 7,707

Term of patent 14 years

(Cl. D56—4)

Fig. 1

Fig. 2

Fig. 3

Fig. 4

FIG. 1 is a perspective view of a base for a phonograph turntable or similar article showing my new design,

FIG. 2 is a front elevation,

FIG. 3 is a rear elevation, and

FIG. 4 is a side elevation.

The broken line showing of a phonograph turntable is for illustrative purposes only. A portion of FIGS. 1 and 2 has been shaded to indicate contrast in appearance.

I claim:

The ornamental design for a base for a phonograph turntable or similar article, substantially as shown and described.
